HIGH TENSION SWITCH

George L. Carlisle, Kenova, W. Va., assignor to
 Delta Star Electric Company, Chicago, Ill., a
 Corporation of Illinois

Application October 14, 1929. Serial No. 399,624

7 Claims. (Cl. 200—48)

This invention is a switch for high tension electric lines.

One of the objects of the invention is to provide an air break switch for high tension lines constructed of few parts and easy to operate. A further object is to provide a switch of the character mentioned so constructed that arcing is reduced to a minimum during operation. A further object is to provide a switch structure so arranged that a movable switch arm may be disengaged from a fixed contact clip by a preliminary rectilinear motion, and a subsequent arcuate movement imparted to the arm, and said arm may be reengaged with said contact clip by a reversal of these movements. A further object is to provide simple means controlling the travel of the switch blade so as to insure the different movements thereof in predetermined sequence. A further object is to provide simple torsion means to assist the opening and to cushion the closing movements of the switch.

The invention will be hereinafter fully set forth and particularly pointed out in the claims.

In the accompanying drawings:—

Figure 1 is a top plan view of a switch constructed in accordance with the invention. Figure 2 is a side elevation. Figure 3 is a detail sectional view illustrating the torsion means, the other features of the switch being omitted. Figures 4 and 5 are detail views illustrating the controller cam. Figures 6 and 7 are detail plan and side views respectively, illustrating the operating mechanism.

Referring to the drawings, 10 designates a base provided with standards 11 and 12, upon which are mounted insulators 13 and 14 respectively, of any desired capacity and construction. Also mounted in said base is a tubular standard 15 in which is rotatably mounted a support 16, on which is mounted an insulator 17 of any desired capacity and construction.

Supported by the insulator 14 is a stationary contact clip 20 of any desired construction, mounted on the base which carries said clip are guide members 22. Rigidly mounted upon the insulator 13 is a plate-like portion 23, of a support member S. Said support member is provided with arms 24, diverging from the plate-like member 23. Said member 23 is provided with a hub like portion 25, which is rigidly attached to the insulator 17, the standard 16 extending through said hub 25, as shown. If desired, a static shield 21 may be interposed between the insulators 13 and 16 and the support member S. The arms 24 are provided with spaced apart bearing lugs 26,

between which is pivotally mounted a link member L, provided with a cross bar 28, which projects between and is pivotally connected with the arms of a yoke member Y. Said yoke member is rigidly secured to the adjacent end of the switch arm or blade 29, so that the free ends 30 of said yoke member project rearwardly toward the hub 25, over and beyond the pivot shaft 31 of said link member L. A roller 32 is revolvably supported between said free ends 30.

Secured to the pivot shaft 31 is one end of a torsion arm T, the other end extending under the switch arm 29, and being provided with a widened portion at its extremity which bears against the underside of the blade. Said torsion member is maintained under spring tension by suitable means preferably by the device illustrated in Figure 3. Referring to said figure, the torsion member T carries a fixed shaft 26a upon the projecting portions of which are rotatably mounted sleeves 27 which are of angular cross section. Each sleeve is encircled by a helical spring 35, which may be anchored in any desired manner.

As shown in the drawings, one end portion of the spring indicated at 35a is angularly bent to conform to the cross sectional contour of the sleeve so that it will not rotate with respect thereto. The other end portion of the spring is preferably soldered or brazed to the adjacent portion of the shaft 26. The projecting portions of the shaft 26a, and the portions of the sleeves 26 which are encircled by the springs 35 are enclosed in suitable casings 34, all of which are clearly shown in the drawings. The arrangement is such that the sleeves 27 and the shaft 26a are so connected by the springs as to maintain a tension upon the torsion member T for a reason to be later described preferably by the device illustrated in Figure 3. Referring to said figure, the torsion member T carries a fixed shaft 26a of circular cross section, upon the projecting portions of which are rotatably mounted sleeves 27, which are provided with angular peripheries. Each sleeve 27 is encircled by a helical spring 35, which may be anchored in any desired manner.

As shown in the drawings, one end portion of the spring indicated at 35a is angularly bent to conform to the peripheral contour of the sleeve, so that the spring will not rotate with respect thereto. The other end portion of the spring is preferably soldered or brazed to the adjacent portion of the shaft 26a. The projecting portions of the shaft 26a, and the portions of the sleeves 27, which are encircled by the springs 35 are enclosed in suitable casings 34, all of which are

clearly shown in the drawings. The arrangement is such that the sleeves 27 and the shafts 26^a rotate one with respect to the other, and are so connected by the springs as to maintain a counterbalancing tension upon the torsion member T for a reason to be later described.

10 The yoke member Y is provided with lugs 36 to which one end of a link 37 is pivotally connected. The other end of said link is pivotally connected to a crank arm 38, rigidly secured to the upper end of the standard 16.

15 Rigidly carried by support member S is a stop member C, which is provided with an abutment 39 in its forward portion, and a curved cam-like surface 40 at the rear thereof. Said member is rigidly supported and has a general hook-like appearance when viewed in side elevation. It will be noted that the abutment 39 is positioned in the path of movement of the cross bar 22.

20 The assembly above described constitutes a single switch unit and any desired number of said units may be arranged in a row as may be desired.

25 The standard 16 may be rotated in any desired or well known manner commonly practiced in the art. For purposes of illustration (Figures 6 and 7), the standard 16 is shown as provided with a crank arm 50, to which is pivotally connected one end of a link 51. The other end of said link is movably connected with a crank arm 52, carried by a rotatable shaft 53 which is mounted in hubs 54, carried by brackets 55, which may be secured to a fixed support of any character. The lower portion of the shaft 53 is provided with a second crank arm 56 in which is pivotally mounted a handle 57. By moving said handle from the full line position of Figure 7 to a horizontal position at right angles thereto, power may be applied to the crank arm 46 to rotate the shaft 53. Obviously, rotation of said shaft will impart rectilinear movement to the link 51. In order to operate a plurality of the switches in unison, each standard 16 is provided with a second crank arm 60, which is connected with a link 61, so that rotation imparted to one of said standards 16 will impart corresponding rotation to the other standards 16 of the group.

30 Assuming the parts to be in the circuit closed condition illustrated in Figure 2, the operation is as follows:—

35 Rotation of the standard 16 through the medium of the shaft 53 and link 51 causes a horizontal arcuate movement of the crank arm 38, and a consequent pulling tension applied by the link 37 upon the switch arm 29 through the yoke member Y. The tendency of said switch arm to move in an arcuate path tending to raise its free end is prevented during pivotal movement of link member L, and until such pivotal movement 40 is arrested by engagement of the cross bar 28 with the abutment 39 of control member C. Therefore the initial pull of the link 37 upon the switch arm 29 results in a rectilinear movement of said arm, rearwardly toward the stop member C. This movement causes the link member L to swing upon its pivotal support until the cross bar 28 has moved into engagement with the abutment 39 of the control member, at the same time increasing the tension upon the counterbalance springs 35. As the link member L moves to the last mentioned position, the yoke member Y has been elevated, so that the roller 31 passes over the end of the stop member C, and comes in contact with the curved surface 40. By this time, the free end of the switch begins to swing upwardly

45 on its pivotal connection 28 with the link member L, and the said curved portion 40 so controls the further movement of the switch arm as to cause it to move in an arcuate path to the final open position. This arcuate movement is greatly assisted by the arm T through the counterbalancing effect created by increased tension of springs 35 caused by the described pivotal movement of link member L. It will be noted that the free end of the arm T slidably engages the underside of the switch blade, so as not to interfere with rectilinear movements of said blade. When the movement of the crank arm 38 is reversed, the cam 40 will first cause the switch arm 29 to move through an arcuate path in the return direction, until said arm assumes a more or less horizontal position, but with the cross bar 28 still in engagement with the abutment 39. Just before said pivot leaves said abutment, the free end of the switch arm will have assumed an approximately horizontal position between the clip members 22, the downward movement being cushioned by arm T, and thereupon the continued movement of the crank arm 38 and the link 37 will cause the switch arm to move in a rectilinear direction toward the clip 20, and slidably over the free end of arm T.

50 The advantages of the invention will be readily understood by those skilled in the art to which it belongs. It will be particularly noted that the switch arm is caused to travel in rectilinear and arcuate paths in predetermined sequence, and that the stop member is so arranged with respect to the other elements of the switch that to assume the opening of circuit breaking position, the switch arm must first travel in a rectilinear path before it can rotate. Likewise, upon operating the switch to close the circuit, it is impossible for the switch arm to move in a horizontal direction until it has first traveled through the predetermined angle of approximately 105° to the horizontal position, after which the supported end of the arm has passed out of engagement with the stop member, and the contact end of the switch arm has engaged the sleeve hood. An important advantage is that auxiliary means are provided for aiding the operating mechanism to move the switch to open position, and to cushion it as it moves to closed position. It will also be observed that a very simple form of air break switch for high tension lines is provided, that it is arranged for easy and accurate operation, and that tendency to produce objectionable arcing is reduced to a minimum.

55 Having thus explained the nature of the invention and described an operative manner of constructing and using the same, although without attempting to set forth all of the forms in which it may be made, or all of the forms of its use, what is claimed is:—

60 1. A switch of the character described comprising a fixed support, a switch blade, a link member pivotally mounted on said support and provided with a cross bar pivotally connected with the switch blade, a movable torsion member engaging said blade, means operated by movement of the link member for applying a yieldable tension to the torsion member, so as to assist the arcuate movement of the blade in the first mentioned direction and to cushion movement of the blade in the opposite direction, and a contact clip cooperating with said switch blade.

65 2. A switch of the character described comprising a fixed support, a switch blade, a shaft mounted to rotate in said support, a link member connected to move with said shaft and provided

- with a cross bar pivotally connected with the switch blade, movably mounted actuating means connected with said switch blade so as to rock said link member on its pivot, stop means for 5 arresting pivotal movement of the link member in one direction, said stop means being positioned to engage said cross bar, so that operation of said actuating means to move the link member in the last mentioned direction will cause the switch 10 blade to first travel rectilinearly and then in an arcuate path, and vice versa during a reversed operation of the actuating means, torsion means connected with said shaft and including a support member slidably engaging said switch blade 15 so as to counterbalance said blade during its arcuate movement, and a contact clip cooperating with the switch blade.
3. A switch of the character described comprising a fixed support, a switch blade, a yoke secured to said switch blade, a link member pivotally mounted on said support and provided with a cross bar connected with said yoke, a rotatable shaft provided with a crank arm, a link connecting said crank arm with said yoke so as to rock 20 said link member on its pivot, stop means lying in the path of movement of the cross bar, so as to arrest movement of the link member in one direction, said stop means being positioned to engage said cross bar, so that operation of said 25 actuating means to move the link member in the last mentioned direction will cause the switch blade to first travel rectilinearly and then in an arcuate path, and vice versa during a reversed operation of the actuating means, counterbalance 30 means connected with the pivotal mounting of said link member so as to be placed under tension during movement of the cross bar toward said stop means, and a pivotally supported arm having one end connected with said spring counterbalance 35 means and having its other end loosely engaging said blade, and a contact clip cooperating with said switch blade.
4. A switch of the character described comprising a fixed support, a link member pivoted at one end to said fixed support, a switch blade connected to the other end of said link member, means for applying an approximately rectilinear pulling force to said blade so as to impart movement to the blade, a stop member mounted on said fixed support and positioned to arrest pivotal movement of the link member in one direction, said pulling means, said stop member and said link being constructed and arranged to impart rectilinear and arcuate movements to said blade in predetermined sequence, and counterbalance 40 means connected with said link and engaging said blade so as to counterbalance the blade during its arcuate movements.
5. A switch of the character described comprising a fixed support, a link member pivoted at one 45 end to said fixed support, a switch blade pivotally connected to the other end of said link member, means for applying an approximately rectilinear pulling force to said blade to impart movement to the blade, a stop member positioned to arrest pivotal movement of the link member in one direction, said pulling means, said stop member and said link being constructed and arranged to impart rectilinear and arcuate movements to the switch blade in predetermined order, spring 50 counterbalance means connected with said link member and so arranged as to be placed under increased tension during movement of the cross bar toward said stop member, and a torsion arm pivoted at one end to said link member and connected with said counterbalance means, the other end of said torsion arm loosely engaging the switch blade, so as to counterbalance said blade during arcuate movement thereof.
6. A switch of the character described comprising a fixed support, a link member pivoted at one end to said fixed support, a switch blade connected to the other end of said link member, means for applying an approximately rectilinear pulling force to said blade to impart movement to the blade, a stop member positioned to arrest pivotal movement of the link member in one direction, said pulling means, said stop member and said link being constructed and arranged to impart rectilinear and arcuate movements to the switch blade in predetermined order, torsion means connected with said link and so arranged as to be placed under increased tension during movement of the link in one direction, and a torsion arm connected at one end with said counterbalancing means and having its other end movably engaging said switch blade.
7. A switch of the character described comprising a fixed support, a link member pivoted at one end to said fixed support and having a cross bar at its other end, a switch blade pivotally connected to said cross bar, means for applying an approximately rectilinear pulling force to said blade to impart movement to the blade, a stop member positioned to engage said cross bar during movement of the link member in one direction, said pulling means, said stop member and said link being constructed and arranged to impart rectilinear and arcuate movements to the switch blade in predetermined order, spring counterbalance means connected with said link member and so arranged as to be placed under increased tension during movement of the cross bar toward said stop member, and a torsion arm pivoted at one end to said link member and connected with said counterbalance means, the other end of said torsion arm loosely engaging the switch blade, so as to counterbalance said blade during arcuate movement thereof.

GEORGE L. CARLISLE. 135
